UNITED STATES PATENT OFFICE.

THOMAS G. AVERILL, OF CHICAGO, ILLINOIS.

FURNACE-DOOR.

1,311,369.

Specification of Letters Patent. Patented July 29, 1919.

Application filed January 2, 1918. Serial No. 209,849.

To all whom it may concern:

Be it known that I, THOMAS G. AVERILL, a citizen of the United States, residing at Chicago, in the county of Cook and State of Illinois, have invented a certain new and useful Improvement in Furnace-Doors, of which the following is a specification.

This invention relates to improvements in furnace doors and has for its object to provide a new and improved construction of this description by means of which the furnace doors can be quickly opened and closed without the operator using his hand for that purpose, and so as to permit coal to be thrown into the furnace. The invention is illustrated in the accompanying drawings wherein,

Figure 1 is a view of a device embodied in the invention showing the doors closed.

Fig. 2 is a sectional view taken on the line 2—2 of Fig. 1.

Fig. 3 is a side elevation of the device shown in Fig. 1.

Fig. 4 is a view of the device illustrated in Fig. 1 showing the doors open and with the air cylinder disconnected.

Fig. 5 is a view of the end of one of the doors and the operating mechanism connected therewith.

Fig. 6 is a plan view of the cylinder and lever illustrated in Fig. 5.

Fig. 7 is a sectional view taken on the line 7—7 of Fig. 5.

Fig. 8 is an enlarged sectional view through the air cylinder.

Fig. 9 is a view of the controlling valve.

Fig. 10 is a view showing the valve rod for the valve shown in Fig. 9.

Fig. 11 is a sectional view showing one means of connecting the foot lever with the door engaging lever.

Fig. 12 is a front view of the parts shown in Fig. 11.

Like numerals refer to like parts throughout the several figures.

I have shown in the drawings a construction particularly adapted to be used with locomotives. In this construction there are two door sections 1 and 2. The door section 1 is pivoted at 3 and door section 2 at 4 on opposite sides of the opening. These door sections are moved simultaneously so as to open and permit fuel to be thrown upon the grate. I have provided three means for opening these door sections, namely, by air,

by foot power, and by hand, and I have also provided means for leaving the door sections partially open for draft purposes. Power for moving the door sections is applied to one of the door sections and the door sections are connected together so as to move in unison by a connecting piece 5 pivoted at 6. The door section 1 is provided with a lug 7, and section 2 with a lug 8, the lug on one door section overlapping the other 60 door section. These lugs, when the door sections are closed, prevent the door sections from being blown out in the event a boiler flue should burst. The door sections may be made of the same weight if desired, and 65 I provide means for insuring their closing without slamming. The means illustrated in Fig. 1 to secure this result comprises a connecting piece 5, and its method of connection with the door sections. It will be 70 noted that the connecting piece 5 is provided with an engaging piece 9 which projects into a slot 10 in section 2, and with an engaging piece 11 which projects into a slot 12 in a piece connecting with section 1. 75 When power is applied to section 1 so as to open the sections, it will be noted that the engaging piece 9 moves farther away from pivot 4 as the door sections open, and closer to pivot 3. This increases the leverage of 80 section 1 and decreases the leverage of section 2. The engaging piece 11 moves a greater distance than the engaging piece 9 so that the top section will always have a sufficient leverage to cause it to automatically 85 close when the pressure applied to it is released. As the door sections close the engaging piece 11 moves away from the pivot 3 and the engaging piece 9 toward the pivot 4, thus equalizing the lever arms and 90 causing the door sections to come together without slamming.

This variation in movement of the two connecting points is secured by the position and arrangement of the connecting piece 5. 100 I prefer to provide the piece 5 with ball bearings at the points where they engage the door sections and the stationary piece behind the door sections. In the construction shown this result is secured by providing the connecting piece 5 with the pinions into which are received the bolts 13 and 14. These bolts engage the door sections and the part behind the door sections as the door sections are moved so as to facilitate the 105 110

movement of the parts. After the door sections are in use, they sometimes wear at the engaging points so that an open space is left between them. It also sometimes happens that the expansion due to the heat causes them to separate so as to leave an opening between them. I provide means for adjusting the door sections so as to compensate for wear, the variations in temperature, etc., so that they may be adjusted to insure the proper closing at all times. In order to secure this adjustment I connect the pivot 6 with an adjustable support 15. This support is adjustably mounted on the rods 16 and held in place by the nuts 17 and 18, the rods being threaded for these nuts. When it is desired to adjust the door sections, the piece 15 is raised or lowered by means of these nuts. It will thus be seen that a fine adjustment can be secured so as to insure the proper closing of the door sections. It will be noted that there is a single connecting piece extending between the door sections and directly connected with them. This construction produces a device with a small number of parts thereby reducing the first cost, and it also produces a simple construction which operates easily and efficiently and which requires little attention or expense to keep in repair. It will further be noted that the connecting piece is located above the door opening, and that there is no cross connecting mechanism below the door sections. This is of importance in locomotive furnaces because the door opening in some furnaces is near the floor and there is little room below the door sections for operating mechanism. It will further be noted that the connecting piece has a direct operative connection with the door sections, and that this connection is movable as the door sections open and close.

The door sections may be opened by hand by means of the lever 19, see Figs. 1, 2 and 3. This lever is pivoted at 20 with a connecting piece 15, and the end 21 thereof engages the fixed part 22 and rides therewith as the lever is moved. It will thus be seen that by moving said lever upwardly the connecting piece 5 would be moved about its pivot so as to open and close the door sections. When the lever 19 is in its maximum open position, the door sections will be held wide open. It is sometimes desirable to provide a small opening between the door sections. This may be done by moving the lever 19 up a short distance and then moving the stop 23 underneath said lever so that it passes between the lever and the connecting piece 5, thereby preventing the lever from returning to its closed position. This stop is pivoted at 24 to the lever 19 and normally rests on top thereof as illustrated. The door sections may be also opened and closed by air pressure or by the foot of the

operator. The construction for opening by air pressure is illustrated in Figs. 1, 5 and 8 to 10. There is provided for this purpose an air cylinder 25 which has a piston 26 and a piston rod 27, said rod being connected with the door 1. This connection is secured by a pin 28 which works in a slot 29. The end of the piston rod is preferably bifurcated and the portion of the door section containing the slot 29 passes between these bifurcations as shown in Fig. 3. The pin 28 can be removed if desired as where for any reason air cannot be supplied or there is some defect so that the air device does not properly operate. The piston 26 (see Fig. 8) is elongated and is enlarged at its lowered end so as to form a surface 30. There is a space 31 between the portion of the piston and the wall of the cylinder. A valve 32 controls the admission of the air to the cylinder 25 and the exhaust of the air therefrom. When the valve 32 is moved upwardly it opens the admission port 33 and lets air in beneath the piston 26. The piston is then moved upwardly so as to apply pressure to the door section 1 and open it, and the connecting piece 5 opens the door section 2. The end of the connecting piece connected with door section 1 moves upwardly and the end connected with door section 2 moves downwardly so that the two door sections are moved in opposite directions to open the door. When the valve 32 moves back to its initial position, the exhaust port 34 is opened and the air passes out of the cylinder through the exhaust port 34 and into the opening 35 in the valve and then out through the port 36 (see Fig. 8). I prefer to provide means for slowing down the movement of the piston near the limit of its down stroke. This result is secured by arranging the port 34 so that it is shut off by the piston before the piston reaches the end of its downward movement. The air in the cylinder below the piston, after the port 34 is closed by the piston, then passes out through the port 33 to the by-pass 37 and then through said by-pass to the port 34. This by-pass is controlled by the screw valve 38 so that the escape of the air is retarded, said valve being arranged so that there is only a small opening which can be regulated as desired. This produces a cushioning effect and slows down the movement of the piston 26. The air enters the chamber of the valve through the pipe 39 connected to any suitable source. There is a port 40 which connects with the space 31 in the cylinder so that there is a pressure on the face 30 of the piston which produces an unbalanced condition, thereby causing the piston to be moved downwardly when the exhaust port is open. The valve 32 is connected with a rod 41 which projects from the valve casing and which is engaged

100

105

110

115

120

125

130

by a foot lever 42 pivoted at 43 (see Fig. 7). When the operator places his foot on the end of the lever 42 he moves the valve 32 upwardly by means of the rod 41, thus admitting air below the piston and causing the door sections to be opened. When he takes his foot from the lever the valve 32 is returned to its initial position. If, for any reason, it is desired to open the door sections by means of the foot, the pin 28 which connects the piston rod 27 with the door section 1 is removed, thus disconnecting said piston rod from the door section as shown in Fig. 4. The foot lever 42 is provided at its end with a pin 44 which works in an opening in a push rod 45 (see Figs. 5 and 7). This pin works freely in this push rod when the door sections are being moved by the air cylinder. When the air cylinder is disconnected from the door sections a pivoted stop 46 (see Fig. 7) is moved into the position shown in Fig. 11 so that the pin 44 engages this stop as clearly illustrated in Fig. 11. Under these conditions when the foot lever is moved the push rod 45 is also moved. This push rod is provided with a slot 47 through which a pin 48 connected to a stationary part, passes. The push rod is provided at its upper end with an engaging face 48 which engages door section 1, as shown in Fig. 1, and which is arranged so that when the push rod is moved upwardly by the foot lever the point of engagement between it and the door section gradually travels over toward the pivot of the door section clearly shown in Fig. 4, thus increasing the leverage of the door section 1 so that it will automatically close when the pressure is released. This construction also causes a decrease in the travel of the push rod, that is to say, the fact that the engagement with the push rod travels nearer to the pivot as the push rod is moved up, gives a greater movement to the door with a less movement of the push rod. When the foot lever is released, the weight of the door moves the parts back to their initial positions. If it is desired to again move the door section by air the pivoted stop 46 is moved to the position shown in Fig. 7, and the piston rod 27 connected to the door section by means of the pin 28. The rod 44 is provided with a cut away portion or notch 44^a into which the projecting point of the stop 46 is received when the push rod is not connected with the foot lever. A spring 44^b keeps the stop 46 in proper position at all times. When it is desired to connect the push rod with the foot lever, it is only necessary to lift up the outer end of the foot lever so as to lower the rod 44 whereupon the upper end of said rod passes below the projecting part of the stop 46 so that said rod engages said stop as shown in Fig. 11. It will thus be seen that I have

here a construction which can be opened by air, by hand, or by the foot of the operator. I have described in detail a particular construction embodying the invention, but it is of course evident that the parts may be varied in many particulars without departing from the spirit of the invention as set forth in the claims hereof, and I therefore do not limit myself to the construction shown.

I claim:

1. A furnace door comprising two door sections, two pivotal connections one for each door, said pivotal connections being on opposite sides of the door opening, a single connecting piece extending from one door section to the other and pivoted between its ends, said connection piece bent so that portions thereof are opposite said door sections, and a direct operative connection between 85 said connecting piece and said door sections.

2. A furnace door comprising two door sections, two pivotal connections one for each door, said pivotal connections being on opposite sides of the door opening, a single connecting piece extending from one door section to the other and pivoted between its ends, a direct operative connection between said connecting piece and said door sections, and means for adjusting said connecting piece so as to adjust the two door sections with relation to each other to insure the proper closing thereof.

3. A furnace door comprising two door sections, two pivotal connections one for each of said door sections, said pivotal connections located on opposite sides of the door opening, a single connecting piece located above the door sections and extending across from one door section to the other, 100 said connecting piece pivoted between its ends, said connecting piece bent so that portions thereof are opposite said door sections having a direct movable connection with each of said door sections.

4. A furnace door comprising two door sections, two pivotal connections one for each door, said pivotal connections being on opposite sides of the door opening, a single connecting piece extending from one door section to the other and pivoted at a point above the door sections said connecting piece projecting on opposite sides of the door opening, and overlapping the door sections, and a movable connection between the door sections and the overlapping portions of said connecting piece.

5. A furnace door comprising two door sections, pivotal connections for said door sections, a connecting piece extending across from one door section to the other, said connecting piece operatively connected with said door sections, a pivot for supporting said connecting piece, and an adjustable support with which said pivot is connected 125

4
whereby the connecting piece may be adjusted to adjust the meeting edges of said door sections.

- 5 6. A furnace door comprising two door sections, two pivotal connections one for each door, said pivotal connections being on opposite sides of the door opening, a single connecting piece extending from one door section to the other and pivoted between its 10 ends, an operative connection between said connecting piece and said door sections, and a lug on each door section which overlaps the other door section when the door sections are closed.
- 15 7. A furnace door comprising two door sections, two pivotal connections one for each door, said pivotal connections being on opposite sides of the door opening, means for applying power to one of said door sections, a connection between the two door sections so that they move in unison and means for varying the connecting points between said connection and said door sections as the door sections are opened and 20 closed.
- 25 8. A furnace door comprising two door sections, two pivots one for each door sec-

tion, said pivots located on opposite sides of the door opening, a connecting device extending from one door section to the other 30 and connected with both of said door sections, and means for automatically varying the points of connection between said connecting device and said door sections as the door sections are opened and closed so as 35 to vary the lever arm of the door sections.

9. A furnace door comprising two door sections, pivots on opposite sides of the door opening and with which said sections are connected, means for applying power to one 40 of said sections, a connecting piece extending from one section to the other and pivoted between its ends, engaging pieces connected with said connecting piece, said door sections being provided with slots into which 45 said engaging pieces are received.

In testimony whereof, I affix my signature in the presence of two witnesses this 29th day of December, 1917.

THOMAS G. AVERILL.
